UNITED STATES PATENT OFFICE.

EMIL J. SIMON, OF NEW YORK, N. Y.

SPARK-GAP FOR THE PRODUCTION OF POWERFUL ELECTRICAL OSCILLATIONS.

1,253,103.

Specification of Letters Patent.

Patented Jan. 8, 1918.

Application filed June 24, 1912. Serial No. 705,516.

To all whom it may concern:

Be it known that I, EMIL J. SIMON, a citizen of the United States, residing in the city, county, and State of New York, have made a certain new and useful Invention in Spark-Gaps for the Production of Powerful Electrical Oscillations, of which the following is a specification.

This invention relates to spark gap structures for use in the production of powerful electrical oscillations.

The object of the invention is to provide a spark gap structure which is simple and efficient.

15 A further object of the invention is to provide a spark gap of unit construction, that is, a spark gap device composed or made up of units, each unit comprising at least one spark gap space between suitably 20 opposed electrodes, and which space is maintained air tight.

A further object of the invention is to provide a unit construction of spark gap wherein the electrodes composing each unit 25 of the spark gap are held together independently of the other units and under sufficient pressure to secure air tightness therebetween and constitute or form the unit, the complete spark gap being composed of a 30 plurality of such units, whereby the complete spark gap may be easily assembled by bringing together any desired number of independent units, and may be easily repaired by removing and replacing individual units.

35 Other objects of the invention will appear more fully hereinafter.

The invention consists substantially in the construction, combination, location and relation of parts, all as will be more fully hereinafter set forth, as shown in accompanying drawing, and finally pointed out in the appended claims.

Referring to the accompanying drawing:—

45 Figure 1 is a view in diagram, showing the circuit relation of an apparatus for generating and radiating powerful electrical oscillations, the diagram illustrating a conventional form of generating and radiating apparatus.

50 Fig. 2 is a view in central section of a spark gap unit embodying the principles of my invention.

55 Fig. 3 is a face view of the unit, comprising or forming my invention.

The same part is designated by the same

reference sign wherever it occurs throughout the several views.

In the accompanying drawing I have shown a unit of the spark gap composed of 50 three plates, namely, two outer and an interposed or intermediate plate, but I wish it to be distinctly understood that my invention, in the broadest scope thereof, as defined in the claims, is not to be limited or 55 restricted to the employment of three electrode plates. And while I have shown my invention as applied to plates which are of circular or generally circular form, it is to be understood that my invention in its 60 broadest scope, and as defined in the claims, is not to be limited or restricted in this respect.

In the particular form shown, the intermediate plate, which I have designated by 75 reference numeral 2, is provided, on each side face thereof, with a seat or recess 4, preferably, though not necessarily, circular in outline, into which is inserted an electrode member 5. In practice I prefer to 80 make the disk member or plate 2, of metal. Any suitable metal may be employed for this purpose. The electrode member 5, which is seated in the recess in the face of the plate 2, is preferably of good thermal as well as 85 electrical conducting material, such, for instance, as electrolytic copper. This electrode member 5, is secured in its seat in the face of the plate 2, in any suitable or convenient manner. I have found it a convenient arrangement to solder said insert or electrode plate 5 into its seat.

Associated with the disk or member 2, is a coöperating member or disk, or plate, as above defined, which I have designated by 95 the numeral 1. The opposed surface or side face of the member 1, is similarly provided with a seat or recess 6, therein in which is similarly seated and secured a coöperating electrode member 7. The opposed surfaces 100 of the electrode members or inserts, 5, 7, fixed or seated in the recesses 4, 6, of the opposed faces of the plates or disks 1, 2, are preferably separated from each other a suitable and convenient distance apart. This 105 separation is accomplished, or may be accomplished, in any suitable or convenient manner. I have shown a simple arrangement wherein raised bosses or rims 8, are formed in the opposed faces or surfaces of the plate members 1, 2 and preferably in the 110 form of raised annuli surrounding the elec-

trode plates 5, 7, therein and which surfaces 8, are arranged to be brought into contact or bearing relation with interposed packing when the plates are assembled. It is exceedingly important, and in fact necessary, 5 that the air gap space between the opposed faces of the electrode members 5, 7, be maintained absolutely air tight and the individual members composing the unit electrically 10 insulated from each other. This may be accomplished in many specifically different ways. I have shown a suitable arrangement for accomplishing these purposes wherein I have interposed between the bearing 15 surfaces of the raised annuli 8, of the plates 1, 2, a suitable air tight insulating material which I have indicated at 9 in the drawing. This may be of any suitable material capable of maintaining the joints between the raised surfaces 8 of the assembled 20 plates perfectly air tight and electrically insulated.

In the form shown the plate 2, is provided with seats or recesses in both the faces thereof 25 of and an additional or third plate 3, is associated with the other side thereof from the plate 1. Where three plates constitute or compose the unit of the gap device, the outermost plates are provided with seats or recesses 6 and inserted electrode plates 7, 30 only on their inner faces, while, the intermediate plate 2 is provided with seats or recesses 4 and inserted plates 5, on both faces thereof. Where three plates are employed for the unit the intermediate plate 35 is separated in like manner as above described from both of the outermost plates by interposed raised bosses 8 and an interposed air-tight and insulating packing. 40 While I have mentioned the fact that two or three plates assembled together constitute a unit of the gap structure, it is to be understood that my invention is not to be limited or restricted in this respect as a larger number 45 of plates may also be assembled together to form the unit of the gap device.

In accordance with the essential characteristics of my invention the complete spark gap is composed of a plurality of the units 50 such as above described. It is also an essential characteristic of my invention that each unit is self contained. That is to say, a unit is composed of two or more plates which are held together as a unit under sufficient degree of pressure to insure absolute air-tightness between the spark gap space therebetween. In the arrangement shown 55 where three plates are employed, I employ an insulating screw bushing construction 10 for pressing together the plates composing the unit. The screw bushing device 10 is employed to secure the desired degree of pressure between the individual plates or members composing the unit in order to accomplish the result of securing air-tightness 60

between the electrode surfaces or in the gap between the electrode surfaces thereof. It is exceedingly important to maintain the opposed surfaces of the electrode members 5, 7 in absolutely parallel planes and a fixed 70 distance apart. In the use of the apparatus the spark occurs or jumps between these surfaces and any irregularity in parallelism of the two surfaces composing a pair of electrodes, or any variation of their distance 75 apart introduces irregularities which interfere with the proper functioning of the apparatus as a spark gap device. For this reason the means employed for securing the desired degree of pressure between the individual members composing each unit, must be so designed and constructed as to secure 80 equality of pressure all the way around between the individual members or plates composing the unit. To this end I prefer to employ suitable screw connections at three different points equally spaced apart peripherally around the plates, where circular plates or disks are employed, that is to say, three of such connecting devices operating 85 from each side of the complete unit, making six connections in all. By this arrangement I am enabled to secure a most uniform degree of pressure and to maintain the plates in absolute alinement and parallelism with 90 respect to each other. It is obvious that other than the specific structure of pressure means shown may be employed without departure from the spirit and scope of my invention, the essential feature being that each 95 unit of the gap construction contains within itself the means or devices for securing the pressure of the members composing the units with reference to each other, and of sufficient degree to secure air-tightness in the air 100 gap spaces thereof. The complete spark gap device is made up by assembling together a plurality of individual units constructed as above described. To this end the outer 105 faces or side surfaces 11, of each unit are made smooth or plain for electrical contact with the corresponding surface of the next adjacent unit assembled therewith. Of course it is unimportant whether the elements or units composing the spark gap 110 structure be in surface or physical contact with each other. They may be suitably separated but electrically connected together in any suitable or convenient manner. A more simple or compact arrangement is secured 115 where they are placed side by side and against and in contact with each other. Any desired number of the units may be assembled together to make up a complete spark gap. In practice I prefer to employ 120 the screw pressure securing devices 10, for the individual members of each unit at the outer or peripheral edges of the plates or members as clearly shown in the drawing.

A spark gap structure embodying the 125

principles of my invention may be used in any desired situation and in connection with any desired circuit arrangement or apparatus employed for generating and radiating 5 electro-magnetic oscillations or for producing powerful electrical oscillations.

In Fig. 1, I have shown in diagram an illustration circuit arrangement adapted for use in connection with a spark gap construction embodying my invention. In this view of the drawing, reference letter E designates the generator or source of current. This, while shown as an alternating current source of power, may obviously be any other 10 form of generator. The circuit of the generator is coupled through a transformer, PS, with an oscillating circuit. The terminals of the secondary of the transformer are bridged by a circuit connection containing a condenser C, in the usual manner. Arranged 15 in one of the leads of the circuit of the secondary of the transformer and bridged by the condenser C, is located the spark gap structure forming my invention. This spark 20 gap structure is indicated generally by reference letter G, and the individual units of the spark gap device are designated respectively by G₁, G₂, G₃, G₄, G₅. Included in 25 series with the spark gap device is the inductive coupling member L₁, associated with which, in the particular form shown, is an inductive coupling member L₂. The latter is arranged in the circuit of an antenna earth system O, B, in which, if desired, may 30 be located an adjustable tertiary inductance L₃, and an ammeter A. However, the details of the construction of the generating 35 and radiating apparatus, and the method of coupling the generating system to the radiating system, are immaterial so far as my present invention is concerned and may be varied and altered within a wide range according 40 to present knowledge of the development of the art without departure from the spirit and scope of my invention. The arrangement shown is purely for illustrative 45 purposes, for indicating the manner of use of the spark gap structure forming my present invention.

It will be observed that a spark gap structure embodying the principles of my invention attains the well known quenching action of spark gaps of the singing spark or high note systems. It will also be understood 50 that my invention is equally well adapted for use whether for telegraphing or telephoning or for other purposes utilizing powerful electrical oscillations, although for telegraphing purposes, as is well known, a suitable key or interrupter, not shown, will be employed at some convenient point in the generating or radiating systems according to present well understood methods.

A spark gap structure embodying my invention possesses the advantage of easy access

to units for the removal, repair or replacement thereof or of the individual elements composing the units, and that the individual elements composing a unit are held together under pressure in the self contained unit itself and the degree of pressure imposed on the elements is not dependent on the pressure under which the various units are held together.

Having now set forth the object and nature of my invention, and a construction embodying the principles thereof, what I claim as new and useful, and of my own invention and desire to secure by Letters Patent is:

1. A spark gap device for the production of powerful electrical oscillations, comprising a plurality of self-contained individually removable units, each unit comprising a plurality of electrodes spaced slightly apart by insulating and air-excluding material inclosing the sparking space, and said electrodes being held together under pressure by means forming part of the unit structure and serving to hold said electrodes in adjusted position whether assembled as part 80 of the spark gap device or removed therefrom, whereby each unit is independent of the other units and of the gap as a whole.

2. A spark gap device for the production of powerful electrical oscillations, comprising a plurality of individually removable units, each unit comprising a plurality of electrodes held together under pressure with a packing of insulating and air-excluding material between them and inclosing their 90 sparking faces and with their sparking faces separated by an air-tight spark gap space, and means for holding said electrodes together forming part of the unit structure and serving to hold said electrodes in adjusted 100 position whether assembled as part of the spark gap device or removed therefrom, such means being independent of the means by which the electrodes of other units are held together and of the means for supporting or 110 holding the units in place.

3. A spark gap device for the production of powerful oscillations, comprising a plurality of self-contained individually removable units, each unit comprising a plurality 115 of disk shaped electrodes held together with their sparking faces separated by an air-tight spark gap space by annular spacing packing of insulating and air-tight material and by clamping means forming part of the 120 unit structure and serving to hold said electrodes in adjusted position whether assembled as part of the spark gap device or removed therefrom, such means being independent of the other units and of the spark 125 gap device as a whole.

4. A self-contained individually removable spark gap unit, comprising a plurality of electrodes assembled together with opposing faces offset from each other, a pack- 130

ing of insulating and air-excluding material between parts of said electrodes and inclosing the opposing sparking faces thereof, and insulated screw pressure securing devices 5 passing through said electrodes to hold the same and said packing under pressure in assembled relation independently of any other unit.

5. A self-contained individually removable spark gap unit, comprising a pair of electrode terminal plates and an intermediate electrode plate assembled to provide spark gap spaces between the intermediate plate and each of the terminal plates, said 10 plates being held together with packing of insulating and air-excluding material between the plates and surrounding the sparking faces thereof by holding means forming part of the unit structure and independent 15 of any other unit and formed to hold the plates under pressure to provide air-tight spark spaces between the plates.

6. A self-contained individually removable spark gap unit adapted to be assembled 20 with one or more similar units to form a multiple-unit spark gap, said unit comprising a plurality of electrode plates assembled together flat-wise with opposing sparking faces of adjacent plates separated to provide 25 a spark gap space between them, said plates having packing of insulating and air-excluding material between adjacent plates and surrounding the sparking faces thereof, and 30

being held pressed together by a plurality of independently adjustable clamping devices forming part of the unit structure and spaced peripherally about the plates beyond their sparking faces, said clamping devices serving to hold said plates in adjusted position whether assembled in a multiple-unit 40 structure or removed therefrom. 35

7. A self-contained individually removable spark gap unit adapted to be assembled with one or more similar units to form a multiple-unit spark-gap, said unit comprising a plurality of electrode plates assembled together flat-wise and spaced slightly apart by insulating and air-excluding material inclosing the sparking space and being held together under pressure by means forming part 45 of the unit structure and serving to hold said electrode plates in adjusted position whether assembled in a multiple-unit structure or removed therefrom, and the outer faces of the electrode plates being formed to 50 bear against the outer faces of the electrode plates of adjacent units in an assembled multiple unit structure. 55

In testimony whereof I have hereunto set my hand in the presence of the subscribing 60 witnesses, on this 18th day of June, A. D., 1912.

EMIL J. SIMON.
